TOILET FLUSH VALVE GUIDE

Filed Feb. 18, 1930

FIG. 5

INVENTOR.
Roy E. DODSON
BY
A. B. Bowman
ATTORNEY

UNITED STATES PATENT OFFICE

ROY E. DODSON, OF SAN DIEGO, CALIFORNIA

TOILET FLUSH-VALVE GUIDE

Application filed February 18, 1930. Serial No. 429,429.

My invention relates to toilet flush valve guides, and the objects of my invention are:

First, to provide a guide for this purpose which maintains the flush valve in accurate alignment with its seat at all times so as to eliminate leakage of the valve caused by improper seating;

Second, to provide a guide of this class, which, although continuously submerged in the water of the toilet tank, will not deteriorate to a point where it must be broken in order to be removed;

Third, to provide a guide of this class which may be used in connection with practically any type of toilet tank, said guide being adjustable in two directions so that the guide portion thereof may be readily centered over the flush valve;

Fourth, to provide a guide of this class which is particularly adapted to be secured to overflow pipe of a toilet tank;

Fifth, to provide a guide of this class which, when once adjusted in position, may be positively locked in said position; and

Sixth, to provide a guide for toilet flush valves which is particularly simple of construction proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this application, in which:

Figure 1 is a side elevational view of my toilet flush valve guide with adjacent portions of the valve and toilet tank shown in outline or in section; Fig. 2 is a transverse sectional view through 2—2 of Fig. 1, with the guide shown in elevation; and Fig. 3 is an end elevational view from 3—3 of Fig. 2.

Similar characters of reference refer to similar parts and portions throughout the several views of the drawings.

The usual toilet tank A is provided with

a suitable valve seat B at its lower side which connects by a pipe or the like to the toilet bowl. Offset from the valve seat B is an overflow pipe C, which extends vertically along the one wall of the toilet tank and communicates with the passage below the valve seat B through a laterally extending passage B1, as shown by dotted lines in Fig. 1.

The valve member D has a semi-spherical portion which fits upon the valve seat B. The valve D is also a float which, when once lifted from the seat B, is buoyed up by the water in the tank and settles again as the water flows out the valve seat B. When once again seated, the pressure of the water in the tank holds the valve in place. Secured to and extending upwardly from the valve member is a rod E, the upper end of which is enlarged and is engageable by a trip rod F actuated by a trip arrangement.

The rod E requires some form of a guide, the overflow pipe being adjacent usually supports the guide. As various toilet tanks vary in the relative positions of the valve seat B and overflow pipe C, it is necessary that this guide be adjustable so as to be readily adapted to the various styles and makes of toilet tanks. The valve D must be replaced from time to time, and, consequently, the guide must be made removable from the overflow pipe C.

As the guide is submerged practically all the time in the water, various parts thereof corrode and interlock so that great difficulty is encountered in removing the guide. Many times the guide must be broken in order to be removed, necessitating replacement with a new guide. With my guide it is possible to build the parts most damaged by corroding of considerable size, yet maintaining the whole structure light of weight and economical of manufacture.

The guide comprises a relatively wide and thin band member 1, which partially encircles the overflow pipe C and is provided at each end with a radially extending ear portion 1a. The two ear portions extend in substantially parallel relation to each other, and are provided with aligned holes therethrough for receiving the stem portions 2a of a guide

member 2. The stem is relatively large in diameter and is screwthreaded at the ends thereof which extend through the ears 1a, as indicated by 2b.

5 At the extended end the stem 2a is provided with a first nut, preferably a wing nut, which bears against the outer side of one of the ears 1a. A second nut, 4, fits upon the stem 2a and bears against the outer side of the other ear 1a. Between the ears 1a is a 10 third nut 5 which is adapted to bear against the inner side of either ear portion for locking the stem 2a against rotation after it has become properly positioned.

15 The extended end of the stem 2a is enlarged forming a sleeve 2c, having a bore 2d therethrough which receives the valve rod E.

When the band 1 is fitted loosely around the overflow pipe C, the extended sleeve of 20 the guide member 2 may be swung in a circle concentric with the center of the overflow pipe.

By turning the nuts 3 and 4 in the same direction, the stem may be shifted outwardly or inwardly lengthening or shortening the 25 distance between the centers of the overflow pipe and sleeve 2c.

If the nuts 3 and 4 are tightened sufficiently to firmly hold the band in place, these two 30 nuts alone will be sufficient to hold the bore 2d of the sleeve 2c in a vertical position. However, with some types of toilet tanks there is considerable tendency for the rod E to shift out of axial alignment with the valve 35 B, thereby tending to rotate the guide member. In such cases the nut 5 rigidly aids the nuts 3 and 4 and holds the stem to the valve guide member firmly in position.

It is obvious from the construction as illustrated in the drawings and described in the 40 foregoing specification that there is provided a toilet flush valve guide as aimed at and set forth in the objects of the invention, and though I have shown and described a particular construction, combination and arrangement 45 of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

55 1. The combination with a toilet tank having a flush valve rod and overflow pipe of a band member encircling said overflow pipe, a stem extending through and between the ends of said band member, means associated 60 with said stem whereby the ends of said band member are drawn together, securing said band member to said overflow pipe, and said stem to said band member and a guide means at the extended end of said stem for slidably 65 receiving said valve rod.

2. The combination with a toilet tank having a flush valve rod and overflow pipe of a clamp means arranged to fit said overflow pipe, a stem associated with said clamp means, nuts on said stem for drawing said clamp means into clamping relation with said overflow pipe, and securing said stem to said clamp, and a guide sleeve at the extended end of said stem for receiving said valve rod.

70 3. The combination with a toilet tank having a flush valve rod and overflow pipe of a clamp means arranged to fit said overflow pipe, a stem longitudinally shiftable through the adjusting end of said clamp means, nuts on said stem for locking said clamp upon said overflow pipe, and binding said stem relative to said clamp means, and a guide sleeve at the extended end of said stem, for receiving said valve guide.

75 4. The combination with a toilet tank having a flush valve rod and overflow pipe of a clamp means partially encircling said overflow pipe having spaced apart ears forming the adjusting end of said clamp means, a stem extending between and through said ears, means on said stem for drawing the ends of said clamp to each other, whereby said clamp is bound to said overflow pipe and said stem is locked relative to said clamp, 80 and a guide means at the extended end of said stem for receiving said valve rod.

85 In testimony whereof, I have hereunto set my hand at San Diego, California, this 7th day of February, 1930.

100 ROY E. DODSON.
